[57] CLAIM

The ornamental design for a pendant, as shown and described.

DESCRIPTION

FIG. 1 is a top plan view of a pendant showing my new design;

FIG. 2 is a right side elevational view;

FIG. 3 is a front elevational view;

FIG. 4 is a front perspective view, the broken line showing of a model, necklace, 3 units and ornamentation therein is for illustrative purposes only and forms no part of the claimed design;

FIG. 5 is a front elevational view, the broken line showing of additional units and the ornamentation therein is for illustrative purposes only and forms no part of the claimed design;

FIG. 6 is a partial cross-section view taken along the lines 6—6 of FIG. 3;

FIG. 7 is a enlarged partial perspective view of the hook and ring linkage between two vertically arranged units;

FIG. 8 is a front elevational view of two units joined side-by-side; and,

FIG. 9 is a front elevational view of two units joined top-to-bottom.

The broken line showing of the additional unit shown in FIGS. 8 and 9 and partial showing in FIG. 7 is for illustrative purposes only and forms no part of the claimed design.

FIG. 6

FIG. 7

FIG. 4**FIG. 5****FIG. 8****FIG. 9**
